UNITED STATES PATENT OFFICE.

ANDREW ESSIG, OF CLEVELAND, OHIO.

HEATER FOR INCUBATORS.

1,137,472.

Specification of Letters Patent. Patented Apr. 27, 1915.

Original application filed May 5, 1909, Serial No. 494,077. Divided and this application filed May 28, 1910. Serial No. 563,940.

To all whom it may concern:

Be it known that I, ANDREW ESSIG, a citizen of the United States of America, residing at Cleveland, in the county of Cuyahoga and State of Ohio, have invented certain new and useful Improvements in Heaters for Incubators, of which the following is a full, clear, and exact description, reference being had to the accompanying drawings, forming part of this specification, which is a division and continuation of my application Serial No. 494,077, filed May 5, 1909, Patent No. 964,467..

My present invention relates to heaters for incubators, and has for its object certain advantageous features of construction and operation, which are explained somewhat in detail in connection with my improved incubator, and are particularly set forth in the appended claims.

In the preferred type of incubator to which my invention is herein applied, there is provided a tank adapted to contain a body of water, used as the principal heat-carrying medium, with which tank are associated suitably regulated flues for transmitting the heat and controlling the heating effect; while associated with the lamp or suitable heating medium is an open outer drum connected with the upper portion of the incubator and affording the same a supply of freshly heated air from the exterior, to maintain a downward circulation within the incubator, the structure being provided with perforated transverse shelves for permitting such circulation. The foregoing, together with other features of construction, will be explained at some length in connection with the accompanying drawings, wherein:—

Figure I is a perspective view of an incubator constructed in accordance with my improvements, wherein certain portions are broken away and shown in dotted lines, better to illustrate the features thereof. Fig. II is a transverse section, showing the features of the lateral channel or recessed tank, and means for turning the eggs therein. Fig. III is a detail illustrating the removable slide for controlling the orifice of the nearer flue; and Fig. IV is another detail

showing the lamp and portions of the ventilating system.

Throughout the several figures of the drawings, I have employed the same character of reference to indicate similar parts. 55

The principal features of construction will be more readily gathered by referring to the perspective view, Fig. I, wherein the parts are sectionally broken away, and one of the doors is shown open, better to illustrate the 60 details of my improved incubator. Within the boxlike casing *a* is provided a tank *b* of peculiar construction, which is adapted to form a nest for the eggs under incubation, and serves to transmit the requisite heat for 65 developing the germs. In order to increase the efficiency, and accordingly the percentage of chicks hatched, I have provided a vertical tank, containing a transverse and two vertical inner flues *b'' b' b²*, which are 70 connected with the lamp *d* and its chimney *d'*, and serve to maintain the desired temperature of the water within the tank. Extending across both vertical faces or side walls of the tank, are channels *c*, which are 75 slightly higher than the short diameter of the egg, so that the eggs may be inclosed upon three sides by the walls of the tank. There are six of these channels on either 80 side of the tank in the incubator shown here- with, and before each of these channels, I preferably provide a perforated guard or shelf *c'*, which will prevent the eggs from being displaced.

Lining the several channels is a continuous strip of fabric *e*, retained in place rearwardly of each channel by means of a wire or strip *e'*, and as this fabric extends rearwardly of the shelves *c'*, and the eggs rest directly upon the fabric against the lower 90 horizontal faces of the channels, it is seen that by pulling the ends of the fabric *e* from top or bottom, will serve to turn the eggs within the channels as is frequently required during incubation. The door *a'* 95 preferably has a peripheral strip of felt *a²* along its edge, and a glass panel *a''* may be inserted within the door frame, in which event there preferably is provided a heavy curtain *a³*, exteriorly of the door for check- 100

ing radiation through the glass. Thus an observation incubator is readily provided. However, as the heat is equally distributed by the fluid within the tank, which is subject to slight variation, and the eggs are so completely inclosed, their temperature is maintained more uniform than in any incubator with which I am acquainted. Heat is imparted therein naturally by direct contact.

10 In order to effect the more ready distribution of the heat, I preferably restrict the opening of the nearer flue b' , as by the movable slide b^4 , so that approximately equal volumes of heated air and gas from the lamp will find exit through these flues or chimneys b' b^2 . The central capped opening b^3 enables the contents of the tank to be replenished from time to time.

15 In order to afford free circulation of freshly heated volumes of air within the incubator, I preferably surround the chimney d' of the lamp d , with a drum d'' open from the bottom and connecting with the top of the incubator casing by means of a pipe d^2 .

20 By this means freshly heated air is constantly supplied at the top of the incubator, and the temperature not only is equalized thereby, since the tank itself is a trifle more highly heated at the bottom, but the depleted air finds constant exit through gauze-covered openings a^4 in the bottom of the incubator casing controlled by slide a^5 . The burner section of the lamp is attached to the drum by means of spring clips d^4 , so that the

25 former may be readily removed for filling the fount or trimming the wick. The usual thermostat t and rod t' may be employed for intermittently lifting the cover d^6 from the chimney immediately the desired temperature

30 is exceeded, through the medium of the weighted lever arm d^6 . Consideration of the foregoing will prove convincing that the eggs, being maintained at a more uniform temperature, surrounded upon three sides as

35 they are by a relatively large body of fluid, will hatch a larger percentage of chicks, than in the ordinary types of incubator. Moreover, the fluctuations of temperature are further minimized by reason of the employment

40 of the system of freshly heated air for ventilating, in conjunction with the incubating tank, while the eggs may be readily turned from time to time, by moving the supporting fabric at either side of the tank, and without

45 danger of breakage or cooling the eggs, as when they require individual handling. Accordingly, I desire to claim my improvements set forth; omitting those details which are desirable only for explaining the structure shown, and pursuant to the statutes specify the following as comprising my invention.

I claim—

1. In an incubator, the combination with

the casing inclosing the incubating-chamber, 65 of an external heating-device, a plurality of permanently-open flues connected therewith and extending through the incubating-chamber in different planes, thermostatic means for controlling the heating-device and an 70 adjustable member having openings of different size, positioned in the flue nearer said heating-device, whereby its orifice is regulated and the heating effect within the chamber may be equalized, substantially as set 75 forth.

2. In an incubator, the combination with an exterior casing, of a fluid tank positioned therein, a lamp for heating the same exterior of the casing, a plurality of normally-open 80 connecting flues communicating with the lamp extending interiorly of the tank, and means comprising a rotatable perforated slide for securing the equalized passage of the heated air and gases through said flues, 85 substantially as set forth.

3. In an incubator, the combination with an exterior casing, of a fluid tank positioned therein, a lamp for heating the same exterior of the casing, a plurality of normally-open 90 connecting flues communicating with the lamp and positioned at different distances therefrom interiorly of the tank, and means comprising a rotatable perforated slide for restricting the orifice of one of the flues for 95 the purpose of diverting an equalized volume of air and heated gas through the other flue, substantially as set forth.

4. In an incubator, the combination with a vertical tank, of means for heating the same, 100 a plurality of perforated shelves extending across the face of the tank substantially in horizontal planes, an exterior casing, and means for ventilating the interior of the incubator transversely of the shelves, comprising 105 an open drum associated with the heating means and connected with the upper portion of the incubator, substantially as set forth.

5. In an incubator, the combination with a 110 vertical tank, of means for heating the same, a plurality of perforated shelves extending across the face of the tank substantially in horizontal planes; said shelves forming guards to prevent displacement of the eggs 115 and supports for the chicks when hatched, an exterior casing, and means for ventilating the interior of the casing from above transversely of the shelves, comprising an open drum associated with the heating means and 120 connected with the upper portion of the incubator, substantially as set forth.

6. In an incubator, the combination with the casing inclosing the incubating-chamber, of an external heating-device, a plurality of normally and continuously open flues connected therewith and extending through the incubator in different planes and at different 125

distances from the heating device, and means
for regulating the passage of heated air and
gases through the flue nearer said heating
device, whereby the heating effect within the
5 chamber is equalized, substantially as set
forth.

In testimony whereof I affix my signature

in presence of two witnesses this seventeenth
day of May, A. D., 1910.
